UNITED STATES PATENT OFFICE

LYMAN F. WHITNEY, OF BOSTON, MASSACHUSETTS, ASSIGNOR TO COMSTOCK & WESCOTT, INC., OF BOSTON, MASSACHUSETTS, A CORPORATION OF MASSACHUSETTS

FLUID PRESSURE APPARATUS

Application filed December 17, 1930. Serial No. 503,006.

This invention relates to an improved heat exchange system and method, and more particularly to a refrigerating apparatus and method employing circulating propellant and refrigerant fluids.

United States Patent No. 1,761,551 to Eastman A. Weaver, dated June 3, 1930, discloses a system of this general type which preferably employs a relatively heavy and non-volatile propellant, such as mercury, and a lighter and more volatile refrigerant such as water. My patent No. 1,761,553, issued June 3, 1930, and my application Serial No. 269,712, filed April 13, 1928, disclose apparatus of this general character in which the propellant may be effective in pumping the refrigerant in a plurality of stages, while the last identified application also discloses such a system in conjunction with a cooler which is disposed above the other component elements of the apparatus, means being provided to pump condensed refrigerant from the refrigerant condenser to the cooler. The copending application of Daniel F. Comstock, No. 502,955, filed on even date herewith, discloses an improved system of this general type in which a portion of the circulating refrigerant may be employed to lift the condensed propellant above the propellant condenser or condensers to the top of a boiler return pipe. Thus this arrangement permits the system to be relatively compact and yet to have a relatively high boiler pressure, which may be balanced by a column of the propellant within the return pipe.

One aspect of the present invention relates to the provision of a system of this general character having an improved arrangement for supplying fluid, such as refrigerant to lift another fluid, such as the propellant in this manner, and preferably affords an auxiliary pump arranged positively to supply refrigerant to the propellant lifter, and arranged so that operation of this lifter is assured whenever operation of the system is initiated. The pump preferably may be self-regulating so that its capacity is automatically varied in accordance with the requirements of the lifter, and so that further supply of refrigerant to the lifter may be inter-

rupted under unusual operating conditions. The secondary or auxiliary pump may be arranged to entrain bodies of condensed refrigerant between propellant globules and to supply the liquid refrigerant to a secondary boiler which includes a refrigerant reservoir and is provided with an elongate passage of restricted diameter which affords resistance to the rapid flow of the refrigerant vapor. The latter is introduced into a duct containing the condensed propellant, this duct being of restricted diameter and arranged to permit the vaporized refrigerant to break off successive globules of the propellant, and to lift the same to the upper part of the propellant return pipe. A portion of the propellant thus lifted may be shunted from the main propellant circuit and is employed to exhaust non-condensable gases from the system, thereby permitting the continued operation of the system at a low or sub-atmospheric pressure. Apparatus of this general character is disclosed for example, in my copending application, Serial No. 174,212, filed March 10, 1927, as well as in my application, Serial No. 269,712, referred to above. Preferably the shunted propellant after passing through the evacuating means or purger passes to the secondary pump which supplies the refrigerant to the secondary boiler and propellant lifter, and then may pass to another pumping means which is effective in lifting the condensed refrigerant to a cooler disposed at a level substantially above the refrigerant condenser.

In the accompanying drawings:

Fig. 1 is a side elevational view of a portion of the refrigerating apparatus, more or less diagrammatic in character, with parts broken away and in section, and certain parts removed for clarity of illustration;

Fig. 2 is an end elevation of a portion of the assembly with parts broken away;

Fig. 3 is a sectional view of an aspirator assembly and a propellant condensing funnel;

Fig. 4 is a broken diagrammatic view of the cooler and related piping;

Fig. 5 is an elevational view of the vaporizer, burner and relating parts;

Fig. 6 is a view partly in section and partly in elevation of the purger and connected piping;

Fig. 7 is an elevational view of the secondary boiler and associated piping;

Fig. 8 is a broken elevational view with parts in section showing the arrangement of the piping employed in conjunction with the secondary pumping means;

Fig. 9 is a sectional detail of a portion of one of the propellant vapor ducts between the boiler and aspirator nozzle;

Fig. 10 is a view partly in section and partly in elevation of a separating chamber assembly that is associated with the refrigerant lifter;

Fig. 11 is a top view of the refrigerant condenser;

Fig. 12 is a sectional detail of the propellant metering or dividing factor, which is effective in dividing the propellant stream to return a part of the lifted propellant directly to the boiler and to divert a part of the same to the purger, secondary pump, and refrigerant lifter;

Fig. 13 is an end elevation of the refrigerant condenser showing related piping and with a part broken away;

Fig. 14 is a section on line 14—14 of Fig. 10; and

Figs. 15, 16, 17, 18, 19, and 20 are diagrammatic views of the secondary pumping means under different conditions.

In accordance with the present invention, a propellant fluid may flow about a propellant circuit which includes a boiler, while a lighter and more volatile refrigerant may flow about a refrigerant circuit which has a part or parts in common with the propellant circuit, where the propellant is effective in causing the circulation of the refrigerant. Preferably separate refrigerant and propellant condensers may be associated with the propellant and refrigerant circuits, while a cooler may be disposed in the refrigerant circuit, and if desired may be disposed at a level substantially higher than the common parts of the circuits and the refrigerant condenser. In the case of a multi-stage system, the propellant system preferably includes parallel portions where energy is imparted from the propellant vapor to successive portions of the circulating refrigerant stream. While a system of this general character may employ many types of working or circulating fluids, a heavy liquid of comparatively high boiling point, such as mercury, is preferred as the propellant, and a lighter more volatile refrigerant such as water is preferred as the refrigerant. With an arrangement of this character, it is only necessary to employ two liquids, not only in the main circuits of the system, but in all of the auxiliary circuits thereof, such as the propellant and refrigerant

lifter, the purger, the secondary pumping means, and the like.

In the accompanying drawings, numeral 1 designates a boiler or vaporizer which may conveniently be associated with a heating factor 2, (Fig. 5) such as a combustion chamber that is provided with a fuel burner 4, which may be supplied by a duct 3 with suitable combustible fluid, such as ordinary illuminating gas. Combustion chamber 2 communicates with the upwardly extending flue 6 for exhaust gases. The boiler is connected to outlet pipes 15 which extend to the aspirator nozzles 19 and 19^a, each of these outlet pipes includes an expandible-contractible element 17, such as a metal bellows, the latter permit the expansion and contraction of the parts adjoining the boiler to occur without throwing undue strain upon aspirator nozzles 19 and 19^a. Preferably these nozzles may be formed of comparatively thin material which is a relatively poor conductor of heat, such as nichrome, and they may form the sole direct connections between the ducts 15, which normally contain hot propellant vapor, and the adjoining portions of the system, which preferably are maintained at a lower temperature.

Ducts 15 also include frusto-conical portions 9 (Figs. 5 and 9) containing frusto-conical screens 10 which are adapted to prevent the passage of foreign particles to the aspirator nozzles. The lower parts of screens 10 may be connected to thimble-like shells 13, each of which contains a central partition 14, with its lower edge somewhat spaced from the bottom of the shell. The frusto-conical portion of each duct 15 is inclined and an opening 8 is provided in the upper side of each shell 13. A closure plate 11 is disposed above the half of the shell adjoining opening 8 so that a trap is provided for the collection of condensed propellant which may pass about the lower edge of partition 14 and out of the opening 8 and thence return to the boiler. This arrangement permits condensed propellant to return to the boiler without necessitating its passage through the relatively finely meshed screen elements 10 which would afford a comparatively high resistance to the passage of globules of liquid propellant, especially if the surface-tension of the propellant is high.

The propellant, for example mercury, is vaporized in boiler 1 and passes upwardly through ducts 15 to aspirator nozzles 19 and 19^a. The latter preferably project into suitable mixing or entraining chambers 20 and 20^a respectively, which are arranged to receive refrigerant vapor. Mixing chamber 20 is connected by a duct 21 with the cooler 12. Duct 21 enters the cooler above the level of the contained liquid in the latter (Fig. 4). Accordingly propellant vapor leaving nozzle 19 at high velocity entrains

refrigerant vapor in chamber 20 and thus causes evaporation of the refrigerant in the cooler. The mixture of propellant and refrigerant vapors passes from mixing chamber 20 to funnel 25, which is aligned with nozzle 19; Fig. 3 illustrates more specifically this portion of the apparatus, the funnel having a portion of restricted diameter spaced from the mixing chamber and preferably having a general downward inclination therefrom. Suitable cooling means, such as fins 26, are associated with the funnel to effect the condensation of the propellant vapor at its comparatively high temperature of liquefaction, as the energy of the same is exhausted in compressing the refrigerant vapor.

Since the temperature of funnel 25 is well above the temperature of condensation of the refrigerant vapor at the pressure conditions prevailing in this part of the system, the refrigerant vapor passes out of the funnel through the upwardly extending duct 30, a continuation of which is connected to the second stage mixing chamber 20^a. The propellant vapor in this mixing chamber is effective in further compressing the refrigerant and pumping the same into the funnel 25^a which is aligned with nozzle 19^a. In general the nozzles, mixing chambers, and funnels for the two stages may be same general type, but preferably the mixing chamber for the second stage pumping means is arranged so that the funnel 15^a is disposed somewhat closer to the outlet of nozzle 19^a than is the case with the corresponding parts of the first stage aspirator assembly.

Suitable drains are provided to receive the condensed propellant from the mixing chambers and funnels, for example, the drains 31 and 31^a may be connected to the lower parts of the mixing chambers to collect any particles of propellant which may have condensed in these parts of the apparatus, while drains 32 and 32^a may be connected to the lower portions of the inclined funnels to collect the major portion of the condensed propellant from the same and from the adjoining refrigerant vapor ducts.

A refrigerant vapor pipe 36 from the second stage aspirator funnel 25^a preferably extends upwardly to a refrigerant condenser which is designated in general by the numeral 40. Figs. 11 and 13 illustrate refrigerant condenser 40 in greater detail; it comprises similar narrow tank sections 34, the pipe 36 being joined to the side of one of these sections intermediate its height. Preferably each of the sections 34 is formed of two similar sheet metal elements which are dished and provided with perimetric flanges 41 which are welded to each other. At the ends of the condenser, suitable plates 42 are joined to ends of the flanges 41 and hold the sections 34 in proper spaced relation to each other. Both of these sections have bottom

portions extending downwardly to outlet pipes 37 and 38 which are joined to a common refrigerant receiving duct 38^a. The tank sections 34 may each be provided with suitable heat dissipating fins 39, and their ends communicate with each other through a short connecting duct 41^a.

The drain 31 may conveniently be joined to the drain 31^a, the latter extending downwardly to a main propellant collecting duct 50 which is disposed adjoining the boiler 1. The upper end of a downwardly extending pipe 45 communicates with the drain 32 below its connection with funnel 25, and the lower part of drain 32^a provides a U-shaped trap which is connected to pipe 45 below its connection with drain 32. The pipe 45 extends downwardly to provide a trap 46 adjoining the lower part of the machine, the opposite leg of this trap being designated by the numeral 47 and extending upwardly to a pipe 70. A downwardly extending pipe 48 of relatively large diameter joins the upper part of pipe 45 with the propellant collecting pipe 50.

The secondary pumping means is designated in general by numeral 49 and includes the tube 38^a which receives refrigerant from condenser 40 and communicates with the upper part of the entraining chamber 51, Fig. 8. Mercury is supplied to the latter from one leg 52 of the trap 53, in a manner which will presently be described. The major portion of duct 54 extending downwardly to a separating chamber 55 has a restricted internal diameter so that condensed refrigerant passing downwardly through the same is entrained between bodies or globules of the propellant which act as separate liquid pistons; thus the pumping means 49 may impose a suitable pressure upon the refrigerant which passes out of the lower end of tube 54 into the separating chamber 55. The upper end portion 54^a of tube 54 may have a greater internal diameter than the remainder thereof, as shown.

A duct 56 has an open end in the upper part of chamber 55 and a duct 57 has an open end below the end of duct 56, but above that of tube 54, so that the lighter refrigerant rising to the upper part of the chamber normally passes into duct 56 and the heavier propellant normally passes into duct 57 while the lower end of tube 54 is always submerged in propellant and sealed against entry of refrigerant. A suitable by-pass duct 80 connects the entraining chamber 51 with the duct 57 below the separating chamber 55. Duct 56 is connected to one end of the upwardly extending duct 70 (Fig. 7) that communicates with a secondary boiler designated in general by numeral 71; this boiler is juxtaposed to flue 6 and comprises a small reservoir 72, which is connected to a tube 73 of restricted internal diameter having a plurality of helical wind-

- ings disposed about the funnel 6 and forming an outlet for the secondary boiler. A continuation 74 of tube 73 is connected to an upwardly extending lifter tube 75 of restricted diameter which forms a continuation of pipe 50. The end of pipe 70 which is joined to duct 56 communicated with leg 47 of the trap 46, as previously described.
- It is evident that the refrigerant entrained in the tube 54 normally separates from the propellant in the separating chamber 55 and passes through pipes 56 and 70 to the reservoir 72. The latter is in direct heat transfer relation to the flue 6, and accordingly the refrigerant is vaporized in this part of the system either in the reservoir or the tube 70 or the tube 73; the latter affords a considerable frictional resistance to the rapid flow of the refrigerant vapor, and accordingly the quantity of vapor which may thus flow through the secondary boiler 71 is restricted. The vapor passing into tube 75 breaks off mercury bodies and is effective in lifting the same through tube 75 to a separating chamber 82. An inclined pipe 83 (Fig. 13) connects the upper portion of the latter to the refrigerant condenser so that the refrigerant vapor received from tube 75 may pass into the refrigerant condenser, there rejoining the main refrigerant circuit and being condensed.
- The liquid propellant passes from the bottom of chamber 82 into a trap 183, a continuation 84 of which is joined to a propellant dividing factor 100. The latter is illustrated in greater detail in Fig. 12, and comprises an outer cylindrical shell 90 and an inner cylindrical member 91 of less height, the walls of the members 90 and 91 being spaced from each other and a sheet metal member 89, having spiral convolutions, being disposed between the members 90 and 91 and thus providing inner and outer spiral passages 92 and 93. The inner passage 92 communicates with the chamber 94, which is above the member 91, so that mercury entering the chamber through pipe 84 may pass downwardly through passage 92 and through an opening or notch 95 at the lower end of the shell, and thence upwardly through the outer spiral passage 93 which communicates with the duct 97. It is evident that spiral passages 92 and 93 afford considerable resistance to the flow of the mercury, and accordingly that the same tends to pile up above the member 91 and overflows into the passage 101 in the central part of the latter. Thus the factor 100 is effective in supplying a fixed or limited quantity of propellant to the purger through the duct 97, and in permitting the remainder of the propellant to pass downwardly through passage 101, which communicates with a propellant return pipe 102. The latter is disposed adjoining the flue 6, and has its lower end communicating with boiler

through a connection 103, Fig. 5. An opening 109 may be disposed in the upper part of the sheet metal element 89, to permit the pressures at opposite sides of the same to be equalized, and a suitable inwardly bent tab 106 is disposed adjoining the mouth of duct 84 to prevent incoming mercury from passing directly to passage 101. The lower part of a gas-collecting chamber 120 is connected by a duct 122 with the refrigerant condenser 40 so that non-condensable gases which occur in the system and are pumped to the refrigerant condenser may pass into chamber 120, while stray refrigerant that passes into chamber 120 may flow back to the refrigerant condenser. A pipe 111 for equalizing pressures connects chamber 120 with the upper part of the chamber 94 of the metering factor 100 and a pipe 123 joins pipe 111 with the entraining chamber 125 of the purger, Fig. 6. The chamber 118, which is connected to pipe 111, may contain a suitable connection for initially evacuating the system and a suitable sealing liquid for this connection, these parts being of conventional type and not being illustrated in detail.

Mercury from the factor 100 passes through pipe 97 to the entraining chamber 125 (Fig. 6). A tube 126 which includes a downwardly extending body portion of restricted internal diameter, has an enlarged upper end disposed within chamber 125. A suitable cylindrical screen 115 is arranged about the upper end of the tube, a closure plate 116 being disposed over the top of the member 115. An opening 117 may be provided in the side of the portion of pipe 126 that projects into the chamber. Thus mercury may pass into the pipe and flow down the same, due to its restricted internal diameter, in the form of successive liquid globules which entrain bodies of gas therebetween. The screen 115 is effective in preventing the clogging of tube 126 with foreign matter. The successive globules of propellant passing downward through the tube 126 serve to entrain and compress the non-condensable gases. The lower end of this tube is disposed concentrically within an outer pipe 127 which normally contains a mercury column, and an opening 129 in the tube 126 permits fluid to flow out of its lower end into the outer pipe. Due to the greater diameter of the outer pipe, the mercury and non-condensable gases separate; the latter bubbling upwardly through the mercury contained in the outer pipe; the upper portion of the latter is connected to a chamber 128 which may be provided with a covering screen 129, and may communicate with the atmosphere; thus non-condensable gases may be exhausted to the atmosphere. It is evident that the atmospheric pressure upon the liquid mercury in pipe 127, plus the weight of that mercury is effective in balancing the internal pres-

sures of the parts of the system communicating therewith.

A pipe 130 is connected to the lower part of duct 127 receiving mercury therefrom and 5 delivering the same to trap 53, preferably an upwardly extending continuation 130^a of duct 130 is connected to the entraining chamber 125, thus, acting as a by-pass should the tube 126 become clogged. Mercury leaving 10 the separating chamber 55 of the secondary pumping means 49 passes into tube 57, which comprises one leg of a trap 58, the opposite leg 58^a of which is connected to an entraining chamber 150 that is disposed above the chamber 55. Chambers 125, 51, and 150 preferably may have the same general internal arrangement. Preferably the portion of trap 15 58 that is joined to chamber 150 may comprise a tube that is flattened to have an oval or substantially elliptical cross-section, and this same expedient may be used in various other parts of the system to reduce the amount of mercury which is required properly to fill the propellant-containing parts of 20 the system.

A drain 152 is connected to the refrigerant condenser above the outlets 37 and 38 and may be joined to the upper end of chamber 150; thus condensed refrigerant is preferentially 25 supplied to the secondary pumping means 49 and thence to the secondary vaporizer 71 and the propellant lifter. During normal operation of the system, however, the refrigerant in the condenser will not only flow to the secondary pumping means 49, but it will also 30 pass through pipe 152 to chamber 150. The lower portion of the latter receives the upper end of a tube 153 of restricted diameter, wherein propellant globules may entrain 35 bodies of the condensed refrigerant, subjecting the same to a considerable liquid head at the lower end of tube 153, which is joined to a separating chamber 155. The latter is shown in greater detail in Fig. 10, the tube 40 153 having an open end disposed adjoining the bottom of this chamber and the refrigerant outlet pipe 158 communicating with the upper part of the chamber. Thus the lighter refrigerant separates from the propellant 45 and passes upwardly through duct 158 under suitable pressure, so that it may be returned 50 to the cooler 12 that is disposed above the remainder of the system; for example, the major portion of the apparatus may be installed in the basement and the cooler may 55 be disposed within a refrigerator upon the first floor.

As shown in Fig. 4, the bottom of the 60 cooler preferably inclines downwardly to the tube 158 which is joined to the lowest corner of the cooler, so that stray propellant particles that pass into the cooler will flow downwardly through tube 158 and thus be received 65 by separating chamber 155. Preferably the lower part of tube 158 is flattened, being pro-

vided with such a shape and dimensions that mercury globules will not form in the same and close its entire area so as to rise with the refrigerant. The open end of a duct 160 is disposed within chamber 155 at a height 70 between the end of tube 153 and the mouth of pipe 158 so that mercury collecting in the lower part of the chamber will overflow into pipe 160 which forms one leg of a trap 161, the opposite leg of which is provided by the 75 drain 32. Thus mercury will pile up in this drain until it reaches the juncture of the same with pipe 45, whereupon the propellant flows into pipe 45, or, the latter being filled, into pipe 48 and thence to the main propellant 80 collecting pipe 50, while tube 153 having its lower end always immersed in mercury, is permanently sealed against blowing back of any refrigerant due to fluctuating pressures.

Preferably the inclined baffles 170 and 171 85 may be disposed below and above the portion of pipe 30 that is located over the propellant condensing funnels 25 and 25^a, (Fig. 2) so that air heated by these funnels or the fins 26 will be diverted from this pipe and 90 from direct impingement upon the fins of the refrigerant condenser 40. Furthermore, this arrangement not only permits the more effective cooling of the refrigerant condenser, but it also facilitates cooling of the refrigerant vapor between the first and second pumping stages, so that the volume of the same 95 that must be pumped may be somewhat reduced and aspirator efficiency in the second stage may be somewhat greater than otherwise would be possible.

In order to aid the thermal efficiency of the system the pipes 75 and 102 are disposed adjoining the flue, which is at a comparatively high temperature when the system is in 100 normal operation. The flue and these pipes preferably are enclosed within a cylindrical casing 170 which may contain suitable powdered insulating material, such as silocel or 105 infusorial earth. A rectangular casing 261, 110 also containing suitable heat insulating material may enclose the lower part of the funnel; the mixing chambers, the propellant vapor ducts 15 and the boiler 1. Thus heat 115 losses are minimized and the hot portions of the system are effectively insulated. It is evident that the funnels 25 and 25^a project from the casing 261 and that the outer portion of the burner which is connected to the gas duct 3 may project from the wall of the 120 casing (Fig. 5.)

In the operation of a system of this character, propellant such as mercury is vaporized in the boiler 1, passing upwardly through ducts 15 to the aspirator nozzles 19 and 19^a. 125 Vapor duct 21 permits refrigerant vapor to flow from cooler 12 to the mixing chamber 20 adjoining the outlet of aspirator nozzle 19, so that the refrigerant is drawn from the 130 cooler, thus causing the latter to have a low

temperature and providing refrigeration. The major portion of the propellant vapor passing from the nozzle 19 is condensed in funnel 25 and the refrigerant vapor passes through pipe 30 to the second stage entraining chamber 20^a where the nozzle 19^a supplies additional propellant vapor to pump the refrigerant vapor through duct 36 to refrigerant condenser 40. The propellant condensing in funnels 25 and 25^a passes into drains 32 and 32^a and thence through pipe 48 to the main collecting pipe 50. The drains 31 and 31^a receive propellant which is condensed in the mixing chambers and are effective in supplying the same to the pipe 50. From drains 32^a the propellant may pass directly through a portion of pipe 45 to duct 48 and thence to the main propellant collecting duct 50, it being understood that normally the leg 45 of the trap 46 is filled with mercury substantially to its juncture with pipe 48. Similarly mercury passing into the drain 32 normally will be received by the upper end of pipe 45 and thus pass to the pipe 48, since the lower part of pipe 32 is normally filled with mercury.

During normal operation of the system refrigerant is vaporized in the secondary boiler 71; the flow of this vapor is somewhat limited due to the restricted diameter of tubes 73, as it passes into the lower end of pipe 75, there being effective in breaking off successive globules of mercury and lifting the same to the separating chamber 82. The refrigerant vapor rises to the upper part of this chamber and passes from the same through pipe 83 to the refrigerant condenser, there rejoining the main refrigerant circuit. The propellant passes to the lower part of the chamber 82, being received by the pipe 83 and passing through its connection 84 to the separating factor 100. As has already been described, this factor is effective in preferentially diverting a portion of the lifted mercury to the purger tube 126, while the remaining portion of the mercury or the propellant is returned through pipe 102 directly to the boiler; it being evident that the pipe 102 contains a liquid column of the propellant to balance the boiler pressure.

Mercury globules passing downwardly through tube 126 entrain non-condensable gases from the chamber 120, which is connected to the entraining chamber 125 of the purger by pipes 111 and 123. The purger will exhaust some refrigerant vapor from the system, especially if an insufficient volume of non-condensable gases are supplied to the purger, it being understood, however, that the amount of refrigerant thus exhausted will be negligible even over a long period of time. The gases bubbling up through the mercury contained in the pipe 127 may pass into the atmosphere, while the mercury passes upwardly through the pipe 130 to the trap 53

and thence to the entraining chamber 51 of the secondary pumping means 49. Liquid refrigerant is there received through pipe 38^a from the bottom of the condenser 40 and is supplied to the separating chamber 55, 70 thence passing through tube 56 and pipe 70 to the secondary boiler 71.

Accordingly it is evident that the pumping means 49 is effective in supplying liquid refrigerant to the secondary vaporizer under an appreciable liquid head due to the weight of the mercury globules in the tube 54. Mercury passing from chamber 55 into trap 58 is received by the entraining chamber 150 of the refrigerant lifter which is supplied with refrigerant from the condenser, and the mercury globules passing downwardly in tube 153 are effective in imposing a suitable head upon the condensed refrigerant, so that the latter, when separated from the mercury in chamber 155, may rise through tube 158 to the cooler, the mercury passing downwardly through trap 151 and filling the leg of the latter which is provided by drain 32 until it overflows into the upper part of pipe 45, thence passing to pipe 48 and the main collecting pipe 50 and in this way rejoining the main propellant circuit.

It is evident that all parts of the system are arranged so that stray propellant may be returned to the propellant containing part of the system. Thus propellant passing to the refrigerant condenser may be received by the drains 37 and 38 and thus pass into the entraining chamber 51, while the cooler is so shaped that stray mercury passing to the same will return through pipe 158.

The secondary boiler 71 and related piping is arranged to insure proper operation of the propellant lifter under all conditions. 105 When there is a tendency for the pressure within the secondary vaporizer to rise excessively thereby vaporizing much more of the refrigerant than is required for the proper operation of the lifter and thereby 110 throwing an excessive load on the refrigerant condenser 40, the rise in pressure mentioned aforesaid causes a rise in the level of the mercury in pipe 54 of the secondary pumping means with consequent decrease of 115 refrigerant fed to the vaporizer. Then the liquid in 72 vaporizes out of the vaporizer more rapidly than water is supplied to it, whereby the refrigerant retreats into tube 70 and the rate of vaporization decreases, since the liquid refrigerant is no longer as near the flue 6. In consequence the pressure in the secondary vaporizer is lowered and more refrigerant is fed thereto, thus causing the level of the vaporizing surface to approach more nearly to flue 6 and in turn increasing the pressure and rate of vaporization to the end that the position of the refrigerant in the vaporizer always tends toward a stable condition.

When the operation of a system of this character is interrupted, for example, due to the stopping of combustion in chamber 2, water will flow by its own gravity head from the lower part of condenser 40 through the tube 54 into pipes 56, 70, and the reservoir 72. Mercury which might otherwise have interfered with this flow is afforded storage space in duct 47 below tube 70, as the mercury in the legs 47 and 45 tends to equalize when the flue 6 becomes cold. Mercury will also be contained in the lower part of the system, including the traps 46 and 161 and the pipe 50. Mercury will also be contained in traps 53 and 58. The duct 38^a, the chamber 51 above the end of tube 54 and the tube 54, will be filled with water, as shown in Fig. 15, while mercury will fill the lower part of chamber 55 up to the mouth of duct 56 and will fill duct 57 and the lower parts of bypass 80 and the duct 58^a.

Under these conditions, if the system is again started in operation by causing combustion to be resumed in chamber 2, there is a relatively large amount of water in direct heat transfer relation to the flue, and as soon as the temperature of the latter is raised, a slight vapor pressure develops in the secondary boiler 71, which will cause the tube 73 to become filled with vapor rather than liquid and mercury to be forced out of tube 74 into pipe 75, and the pressure in chamber 55 will rise, thus forcing the mercury level downwardly in this chamber and causing mercury to rise into the lower part of tube 54 and in the ducts 80 and 58^a so that the secondary vaporizer pressure is balanced by the liquid heads in the tube 54, and ducts 80 and 58^a (Fig. 16).

In starting, until the flue 6 is sufficiently heated, there will not be enough pressure available to cause the mercury to rise in tube 58^a to spill over into chamber 150, and mercury which has come from the funnels and been lifted (as explained in the next paragraph) after passing through the metering device and purger will pass down tube 54 thereby pumping water into the secondary vaporizer; the mercury itself, as it cannot spill into chamber 150, likewise passes down tube 56 into tube 47, spilling over from tube 45 into tube 48 and joining the main body of the propellant to be relifted.

The tube 73 does not afford appreciable resistance to vapor flow at low velocity, i. e., when the system is starting; accordingly, as the pressure continues to rise in the secondary vaporizer, it will be sufficient to permit the vapor from tube 73 to be effective in breaking off a mercury globule in the lower end of pipe 75. Thus, mercury is lifted to the separating factor 100 which, as previously described, preferentially supplies mercury, upon starting, to the purger. Accordingly mercury soon passes from duct 130 into

trap 153 and mercury flows from the upper end of duct 152 into chamber 51 and is received by the upper end of tube 54.

When the first globules of propellant thus arrive at the upper end of the tube 54, the liquid head provided by these globules and the mercury in the lower end of tube 54 will tend automatically to balance the vaporizer pressure. If this pressure has not risen, the level of the mercury in chamber 55 may rise to the mouth of duct 56, as shown in Fig. 17, and as mercury continues to be supplied to the upper part of tube 54, the mercury may temporarily overflow into duct 56, passing downwardly through pipe 47 into the lower part of the system. Under these conditions the mercury columns in tubes 58^a and 80 will remain at such a height as properly to balance the existent vaporizer pressure. As the system continues in operation, this pressure increases, and mercury rises in tube 58^a and spills over into chamber 150, while the mercury level in chamber 55 becomes lower so that it is substantially in the region of the mouth of the drain 57 and so that mercury no longer passes into the duct 56. If the pressure in the vaporizer rises still higher, water may pass from the upper part of chamber 55 into drain 57 so that the mercury is depressed in that drain by the water pressure thereabove and the effective mercury head which substantially balances the vaporizer pressure will be greater than the distance between the spill-over at the top of duct 58^a and the mercury level in chamber 55 (Fig. 18). As the vaporizer pressure thus rises and the mercury head in trap 58 increases the proportion of mercury in the tube 54 will also increase so that the liquid heads will substantially equalize. Thus, means is provided automatically to reduce the amount of water entrained between mercury globules in the tube 54 as the vaporizer pressure increases, and accordingly less water is automatically supplied to the vaporizer as its pressure becomes greater. When the vaporizer pressure falls, the liquid heads in the pumping system automatically adjust themselves to balance the lower pressure, and accordingly less mercury is contained in tube 54 and a larger proportion of water is provided in the same, thus a greater amount of water is pumped to the vaporizer whenever its pressure falls, and the water level moves nearer to flue 6, whereupon the vapor pressure tends to rise.

Should the pressure in the vaporizer approach a predetermined maximum, the proportion of mercury in tube 54 will increase until the mercury fills the tube up to the enlarged portion 54^a, and accordingly further flow of water through 54 is temporarily interrupted (Fig. 19). Such a condition will be reached just before the pressure upon the water in chamber 55 is sufficiently high to

depress the mercury level in drain 57 to the juncture with the by-pass 80. If the pressure in the vaporizer still continues to rise, mercury will continue to pile up in the enlarged portion 54^a of tube 54 to balance this pressure and the mercury level in drain 57 will be further depressed so that the head in duct 58^a may balance the higher pressure. This lowering of the mercury level in drain 57 results in the uncovering of the lower end of duct 80 and permits water to flow from chamber 55 upwardly into the bypass 80, bubbling through the mercury in the by-pass and thus returning to chamber 51 at the upper end of tube 54 (Fig. 20). Accordingly, under extreme vaporizing conditions water may be forced upwardly through duct 56, chamber 55 and thence through drain 57 and the by-pass 80 so that it returns to the chamber 51 above the tube 54, thus automatically permitting increase in the vapor-containing volume of the system in the region of the vaporizer so that the vaporizer pressure falls. In the meantime, the tube 54 will remain filled with mercury. When the vaporizer pressure has thus been relieved, the pressure upon the water in chamber 55 will become lower, the level of the mercury in drain 57 will rise, and the system will resume normal operation. Under all conditions, the lower end of tube 54 is immersed in a body of mercury which acts as a seal and which prevents the vaporizer pressure from forcing mercury out of the tube.

From the foregoing, it is evident that the secondary pumping means 49 provides an arrangement permitting the automatic formation of a liquid head upon starting of the system which will balance the initial vaporizer pressure even before the first increment of mercury reaches the upper end of tubes 54 (Fig. 16); that the chamber 55 and its connections are so arranged that mercury may be drained from the same through duct 56 when the height of the mercury column in duct 58^a is not sufficient to permit the mercury supplied to the secondary pumping means to overflow into chamber 150 (Fig. 17); that the pressure balancing head in duct 58^a will automatically balance the pressure in chamber 55 which is dependent upon the vaporizer pressure and that this arrangement permits the automatic variation of the amount of water supplied to the vaporizer in response to the vaporizer pressure. Accordingly, when the vaporizer pressure reaches a substantially predetermined point further supply of water to the vaporizer is interrupted (Fig. 19); while should the vaporizer pressure continue to rise even above this point, automatic means is provided for releasing water from the vaporizer and automatically increasing the vapor-containing capacity of the adjoining part of the system to relieve the vaporizer pressure (Fig. 20).

It should be understood that the present disclosure is for the purpose of illustration only and that this invention includes all modifications and equivalents which fall within the scope of the appended claims. 70

I claim:

1. Apparatus of the class described comprising a vaporizer, a heating factor associated therewith, a condenser connected to the vaporizer, a secondary boiler adjoining the heating factor, said boiler including an elongate passage of restricted cross section, a return pipe having its lower end connected to the vaporizer, and a lifter pipe of restricted cross section adapted to receive liquid from the condenser and connected to the upper end of the return pipe, said passage being connected to said pipe so that vapor from the boiler lifts condensed fluid to the upper end of the pipe. 75

2. Apparatus of the class described comprising a propellant circuit, a refrigerant circuit, said first circuit including a vaporizer and condenser, said second circuit including a cooler and a second condenser, said circuits having a part in common where vaporized propellant pumps the refrigerant from the cooler to the second condenser, a propellant return duct having its upper end disposed above the first condenser and its lower end connected to the vaporizer, a secondary boiler arranged to receive refrigerant from the second condenser, said boiler comprising a reservoir and an elongate tube of restricted diameter, a lifter pipe of restricted diameter, the tube being connected to the lifter pipe, and means to supply the condensed propellant to the lower end of the lifter pipe, the upper end of the latter communicating with the return duct, whereby vapor from the secondary vaporizer raises the condensed propellant to the upper part of the return duct. 90

3. Apparatus of the class described comprising a propellant circuit including a propellant vaporizer and a propellant condenser, a refrigerant circuit including a cooler and a refrigerant condenser, said circuits having a part in common where the propellant vapor is effective in causing the circulation of the refrigerant, cooling fins disposed about the propellant condenser, and a baffle disposed above the propellant condenser and between the same and the refrigerant condenser to divert air heated by the propellant condenser from rising to the region of the refrigerant condenser. 105

4. Apparatus comprising a refrigerant circuit including a cooler and a refrigerant condenser, and propellant circuits including a vaporizer and separate propellant condensers, said refrigerant circuits and propellant circuits having parts in common where the propellant causes the circulation of the refrigerant in successive parts of its circuit, 110

a refrigerant duct disposed between these successive parts of the circuits, a portion of said duct being disposed above the propellant condensers and below the refrigerant condenser, and baffles disposed between said duct portion and the propellant condensers and refrigerant condenser, whereby air heated by the propellant condensers is diverted from rising to the region of the refrigerant condenser, and whereby the duct portion is protected from direct contact with said heated air.

5

boiling point fluid, heating means associated with the reservoir, a duct of restricted diameter arranged to receive the condensed high boiling point fluid and to receive vapor from the reservoir, whereby the vapor may be effective in lifting bodies of the condensed fluid in said tube of restricted diameter, the upper end of said tube being connected to the duct which returns the heavy boiling point fluid to the vaporizer.

70

75

8. Apparatus of the class described comprising a circuit for a fluid having a relatively high boiling point, said circuit including a

15 said heated air.

5. Apparatus of the class described comprising a propellant circuit including a propellant vaporizer and a propellant condenser, a refrigerant circuit including a cooler and an air-cooled refrigerant condenser, said circuits having a part in common where the propellant vapor is effective in causing the circulation of the refrigerant, cooling fins disposed about the propellant condenser, and an inclined baffle disposed above the propellant condenser, and between the same and the refrigerant condenser, said baffle having a width substantially as great as that of said fins, thereby to divert air heated by the propellant condenser from rising to the region of the refrigerant condenser.

6. Apparatus comprising a refrigerant circuit including a cooler and a refrigerant condenser, and propellant circuits including a vaporizer and separate propellant condensers, said refrigerant circuits and propellant circuits having parts in common where the propellant causes the circulation of the refrigerant in successive parts of its circuit, a refrigerant duct disposed between the common parts of the circuits, a portion of said duct being substantially horizontally disposed above the propellant condensers and below

the refrigerant condenser, and inclined baffles disposed between said duct portion, and the propellant condensers and refrigerant condenser, whereby air heated by the propellant condensers is diverted from rising to the region of the refrigerant condenser, and whereby the duct portion is protected from direct contact with said heated air.

9. Apparatus of the class described comprising a circuit for a fluid having a relatively high boiling point, said circuit including a vaporizer and condenser, and another circuit for a fluid having a relatively low boiling point, said circuit including a condenser, the circuits having a part in common where one fluid is effective in causing the circulation of the other fluid, the apparatus including an upwardly

7. Apparatus of the class described comprising a circuit for a fluid having a relatively high boiling point, said circuit including a vaporizer and condenser, and another circuit for a fluid having a relatively low boiling point, said circuit including a condenser, the circuit having a part in common where one fluid is effective in causing the circulation of the other fluid, a duct extending upwardly from the vaporizer and forming a part of the circuit for the fluid of high boiling point and being arranged to contain a column of said fluid to balance the vaporizer pressure and to return the fluid to the vaporizer, and means to lift condensed fluid to the top of said column comprising a reservoir arranged to retain a supply of the low

the other fluid, a duct extending upwardly from the vaporizer and forming a part of the circuit for the fluid of high boiling and being arranged to contain a column of said fluid to balance the vaporizer therefrom and to return the fluid to the vaporizer, and means to lift condensed fluid to the top of said column, said means including a secondary vaporizer arranged to receive fluid from the condenser for the low boiling point liquid, said secondary vaporizer including a tube of restricted diameter, an upwardly extending lifter duct of restricted diameter having its lower end arranged to receive the condensed high boiling point fluid and connected to the secondary vaporizer, whereby the vaporized fluid may lift successive bodies of the high boiling

point fluid in the upwardly extending duct, the upper end of said duct being connected to a trap, the trap being connected to the upper end of the return duct for the high boiling 5 point fluid, the upper end of the lifter duct also having a connection with the condenser for the low boiling point fluid.

10. Apparatus comprising a fluid circuit and including a vaporizer having a heating factor, an upwardly extending flue associated with said heating factor, a condenser connected to said vaporizer to effect the liquefaction of the vaporized fluid, a return pipe having its upper end disposed above the condenser and arranged to contain a body of the condensed fluid to balance the vaporizer pressure and to return the fluid to the vaporizer, a lifter tube of restricted diameter having its lower end arranged to receive liquid from the condenser and having its upper end connected to the return duct, and means to lift the fluid through said duct comprising a second vaporizer arranged to receive a fluid of lower boiling point, said vaporizer including an elongate tube of small diameter in heating relation to the flue, said tube having a continuation connected to the lifter tube, whereby the vaporized fluid may break off successive bodies of liquid at the lower end of the lifter tube and raise the same to the level of the upper part of the return duct.

11. Apparatus comprising a fluid circuit and including a vaporizer having a heating factor, an upwardly extending flue associated with said heating factor, a condenser connected to said vaporizer to effect the liquefaction of the vaporized fluid, a return pipe having its upper end disposed above the condenser and arranged to contain a body of the condensed fluid to balance the vaporizer pressure and to return the fluid to the vaporizer, a lifter tube of restricted diameter having its lower end arranged to receive liquid from the condenser and having its upper end connected to the return duct, vapor supply means connected to the lower part of the lifter tube and comprising a reservoir arranged to receive another fluid of relatively low boiling point and a helical tube of restricted diameter disposed in heat transfer relation to the flue, said helical tube being connected to the lower part of the lifter tube to permit vapor of the low boiling point liquid to break off successive bodies of the condenser fluid and to lift the same to the top of the return duct.

12. Apparatus comprising a fluid circuit and including a vaporizer having a heating factor, an upwardly extending flue associated with said heating factor, a condenser connected to said vaporizer to effect the liquefaction of the vaporized fluid, a return pipe having its upper end disposed above the condenser and arranged to contain a body of the condensed fluid to balance the vaporizer pressure

and to return the fluid to the vaporizer, a lifter tube of restricted diameter having its lower end arranged to receive liquid from the condenser and having its upper end connected to the return duct, means to supply vapor to the lower end of the lifter tube comprising a reservoir arranged to receive a relatively volatile fluid and an elongate duct of restricted internal diameter connected to the reservoir, said elongate duct and reservoir both being in heat transfer relation to the flue, the elongate duct being connected to the lower part of the lifter tube, whereby the relatively volatile fluid is vaporized and passes into the lower part of the return tube to break off successive bodies of the condensed fluid and to lift the same to the upper part of the return duct.

13. Apparatus comprising a propellant circuit including a vaporizer, a propellant condenser, a refrigerant circuit including a cooler and a refrigerant condenser, said circuits having a part in common where propellant vapor is effective in causing the circulation of the refrigerant, a return duct connected to the vaporizer and having its upper portion disposed above the propellant condenser, a lifter duct connected to the upper portion of the return duct to supply propellant thereto, a duct arranged to receive a portion of the propellant thus raised through the lifter duct, said duct having a restricted internal diameter and being arranged also to receive refrigerant from the refrigerant condenser, a secondary vaporizer, separating means at the lower end of said duct of restricted diameter, said separating means to be arranged to effect the separation of the propellant and the refrigerant, a duct arranged to supply refrigerant from the separating means to said secondary vaporizer, the latter being connected to the lifter tube to effect the lifting of successive propellant bodies therein, a duct connected to the separating means and to the lifter tube to supply propellant from the separating means to the lifter tube, said tube of restricted diameter being arranged to receive the condensed refrigerant from the lowest part of the refrigerant condenser, and a second duct connected to the condenser above its lowest part and arranged to return condensed refrigerant from the condenser to the cooler, whereby refrigerant is preferentially supplied to the tube of restricted diameter and thus to the secondary vaporizer.

14. Apparatus comprising a propellant circuit including a vaporizer and a propellant condenser, a refrigerant circuit including a cooler and a refrigerant condenser, said circuits having a part in common where propellant vapor is effective in causing the circulation of the refrigerant, a return duct connected to the vaporizer and having its upper portion disposed above the propellant condenser, a lifter duct connected to the upper

portion of the return duct to supply propellant thereto, a duct arranged to receive a portion of the propellant thus raised through the lifter duct, said duct having a restricted 5 internal diameter and being arranged also to receive refrigerant from the refrigerant condenser, a secondary vaporizer, separating means at the lower end of said duct of restricted diameter, said separating means to 10 be arranged to effect the separation of the propellant and the refrigerant, a duct arranged to supply refrigerant from the separating means to said secondary vaporizer, the latter being connected to the lifter tube to 15 effect the lifting of successive propellant bodies therein, a duct connected to the separating means and to the lifter tube to direct propellant from the separating means to the lifter tube, and a by-pass duct connected to 20 the duct supplying condensed refrigerant to the tube of restricted diameter and connected to the duct receiving propellant from the separating means, whereby refrigerant may be by-passed when the pressure in the secondary 25 vaporizer becomes relatively high.

15. Apparatus comprising a propellant circuit including a vaporizer and a propellant condenser, a refrigerant circuit including a cooler and a refrigerant condenser, said circuit having a part in common where propellant vapor is effective in causing the circulation of the refrigerant, a return duct connected to the vaporizer and having its upper portion disposed above the propellant condenser, a lifter duct connected to the upper portion of the return duct to supply propellant thereto, a duct arranged to receive a portion of the propellant thus raised through the lifter duct, said duct having a restricted 30 internal diameter and being arranged also to receive refrigerant from the refrigerant condenser, a secondary vaporizer, separating means at the lower end of said duct of restricted diameter, said separating means to 35 be arranged to effect the separation of the propellant and the refrigerant, a duct arranged to supply refrigerant from the separating means to said secondary vaporizer, the latter being connected to the lifter tube to 40 effect the lifting of successive propellant bodies therein, a duct connected to the separating means and to the lifter tube to direct propellant from the separating means to the lifter tube, a trap connected to the duct which 45 directs the refrigerant from the separating means to the secondary vaporizer, said trap being connected to a duct which is arranged to supply propellant to the lifter tube, whereby stray propellant particles passing to the 50 region of the secondary vaporizer may be collected in the trap, and upon the vaporization of fluid in the secondary vaporizer with 55 an increase in secondary vaporizer pressure the propellant from the trap may pass to the 60 lifter tube.

16. Apparatus comprising a refrigerant circuit including a cooler and a refrigerant condenser, a propellant circuit including a vaporizer and a propellant condenser, said circuits having a part in common where the vaporized propellant is effective in causing circulation of the refrigerant, the refrigerant circuit including a vapor duct between said common part and the refrigerant condenser, a secondary vaporizer, secondary pumping means arranged to receive refrigerant from the lower part of the refrigerant condenser and to supply the same to the secondary vaporizer, a lifter tube of restricted diameter arranged to receive propellant from the propellant condenser and vapor from the secondary vaporizer, a propellant return duct connected to the upper end of the lifter tube and to the propellant vaporizer, a pipe between the upper end of the lifter tube and the refrigerant condenser, the connections between the vapor duct and the refrigerant condenser and between the pipe and the refrigerant condenser being disposed at a substantial height above the lowest part of the condenser, and a duct for returning condensed refrigerant from the refrigerant condenser to the cooler, the last-named duct being connected to the condenser above its lowest part but below said connections of the refrigerant condenser with the vapor duct and said pipe, whereby condensed refrigerant is preferentially supplied to the secondary pumping means and then to the cooler. 90

17. Apparatus comprising a refrigerant circuit including a cooler and a refrigerant condenser, a propellant circuit including a vaporizer and a propellant condenser, said circuits having a part in common where the vaporized propellant is effective in causing circulation of the refrigerant, the refrigerant circuit including a vapor duct between said common part and the refrigerant condenser, a secondary vaporizer, secondary pumping means arranged to receive refrigerant from the lowest part of the refrigerant condenser and to supply the same to the secondary vaporizer, said secondary pumping means including a tube of restricted diameter wherein propellant globules entrain bodies of refrigerant, a lifter tube of restricted diameter arranged to receive propellant from the propellant condenser and vapor from the secondary vaporizer, a propellant return duct, a vapor pipe between the upper end of the lifter tube and the refrigerant condenser and means receiving propellant from the tube of restricted diameter in the secondary pumping means and supplying said propellant to the lifter tube, whereby propellant straying to the refrigerant condenser may pass through the secondary pumping means and thus be returned to the propellant circuit. 115

18. Apparatus comprising a circuit including a cooler and a refrigerant condenser, 130

- a propellant circuit including a vaporizer and a propellant condenser, said circuits having a part in common where the vaporized propellant is effective in causing circulation of the refrigerant, the refrigerant circuit including a vapor duct between said common part and the refrigerant condenser, a secondary vaporizer, secondary pumping means arranged to receive refrigerant from the lowest part of the refrigerant condenser and to supply the same to the secondary vaporizer, said secondary pumping means including a tube of restricted diameter wherein propellant globules entrain bodies of refrigerant, a lifter tube of restricted diameter arranged to receive propellant from the propellant condenser and vapor from the secondary vaporizer, a propellant return duct, a vapor pipe between the upper end of the lifter tube and the refrigerant condenser, resistance means associated with said secondary vaporizer to limit the flow of vapor to the lifter tube, a trap receiving propellant from the secondary pumping means, a duct connecting said trap to the lifter tube, and a by-pass between the portion of said trap adjoining the secondary pumping means and the upper end of the tube of restricted diameter in said pumping means, whereby pressure building up in the secondary vaporizer will cause refrigerant to be circulated through said by-pass.
19. Apparatus comprising a refrigerant circuit including a cooler and a refrigerant condenser, a propellant circuit including a vaporizer and a propellant condenser, said circuits having a part in common where the vaporized propellant is effective in causing circulation of the refrigerant, the refrigerant circuit including a vapor duct between said common part and the refrigerant condenser, a secondary vaporizer, secondary pumping means arranged to receive refrigerant from the lowest part of the refrigerant condenser and to supply the same to the secondary vaporizer, said secondary pumping means including a tube of restricted diameter wherein propellant globules entrain bodies of refrigerant, a lifter tube of restricted diameter arranged to receive propellant from the propellant condenser and vapor from the secondary vaporizer, a propellant return duct, a vapor pipe between the upper end of the lifter tube and the refrigerant condenser, the secondary pumping means including a separating chamber, the tube of restricted diameter in said pumping means being a vent in the lower part of the chamber, a propellant outlet duct having a mouth above said vent and being arranged to supply propellant to the lifter tube, a refrigerant duct having a mouth above that of the propellant outlet duct and being connected to the secondary vaporizer.
20. Apparatus comprising a refrigerant circuit including a cooler and a refrigerant condenser, a propellant circuit including a vaporizer and a propellant condenser, said circuits having a part in common where the vaporized propellant is effective in causing circulation of the refrigerant, the refrigerant circuit including a vapor duct between said common part and the refrigerant condenser, a secondary vaporizer, secondary pumping means arranged to receive refrigerant from the lowest part of the refrigerant condenser and to supply the same to the secondary vaporizer, said secondary pumping means including a tube of restricted diameter wherein propellant globules entrain bodies of refrigerant, a lifter tube of restricted diameter arranged to receive propellant from the propellant condenser and vapor from the secondary vaporizer, a propellant return duct, and a vapor pipe between the upper end of the lifter tube and the refrigerant condenser, the secondary pumping means including a separating chamber, the tube of restricted diameter in said pumping means being a vent in the lower part of the chamber, a propellant outlet duct having a mouth above said vent and being arranged to supply propellant to the lifter tube, a refrigerant duct having a mouth above that of the propellant outlet duct and being connected to the secondary vaporizer.
21. Apparatus comprising a refrigerant circuit including a cooler and a refrigerant condenser, a propellant circuit including a vaporizer and a propellant condenser, said circuits having a part in common where the vaporized propellant is effective in causing circulation of the refrigerant, the refrigerant circuit including a vapor duct between said common part and the refrigerant condenser, a secondary vaporizer, secondary pumping means arranged to receive refrigerant from the refrigerant condenser and to supply the same to the secondary vaporizer, said secondary pumping means including a tube of restricted diameter wherein propellant globules entrain bodies of refrigerant, a lifter tube of restricted diameter arranged to receive propellant from the propellant condenser and vapor from the secondary vaporizer, a propellant return duct, the secondary pumping means including a separating chamber, the tube of restricted diameter in said pumping means being a vent in the lower part of the chamber, a propellant outlet duct having a mouth above said vent and being arranged to supply propellant to the lifter tube, and a refrigerant duct having a mouth above that of the propellant outlet duct and being connected to the secondary vaporizer.

22. Apparatus of the class described comprising a vaporizer including an elongate tube of restricted diameter associated with heating means, an outlet connected to one end of the tube, a liquid supply and pressure balancing means connected to the other end of the tube, the amount of liquid in the tube automatically varying in response to increase in vapor pressure, whereby automatic regulation of the amount of vapor passing to its outlet is provided, the pressure balancing and supply means including a tube of restricted diameter wherein globules of a heavier liquid are normally effective in pumping liquid to said vaporizer and a by-pass arranged to cause short-circuiting of the pumping means in response to high pressure in the vaporizer.
23. Apparatus of the class described comprising a vaporizer including an elongate tube of restricted diameter associated with heating means, an outlet duct connected to one end of the tube, a liquid supply and pressure balancing means connected to the other end of the tube, the amount of liquid in the vaporizer tube automatically varying in response to increase in vapor pressure, whereby automatic regulation of the amount of vapor passing to the outlet duct is provided, the pressure balancing and supply means including a tube of restricted diameter wherein globules of a heavier liquid are normally effective in pumping liquid to said vaporizer and means associated with said last-named tube to receive the heavier liquid therefrom and permit a column of the latter to be built up to balance initial vaporizer pressure when operation of the apparatus is started and before the globules of heavier liquid are supplied to the tube of restricted diameter.
24. Apparatus of the class described comprising a circuit for a relatively light and volatile fluid, a second circuit for a heavy and less volatile fluid, said first-named circuit including a vaporizer and a condenser, said circuits having a part in common including a downwardly extending tube of restricted diameter wherein globules of heavy fluid entrain bodies of the lighter liquid, separating means at the lower end of said tube, a duct connecting said means to the vaporizer, a lifter tube of restricted diameter also forming a common part of said circuits, wherein vapor from the vaporizer lifts globules of the heavier fluid, ducts connecting the lower end of said lifter tube with the vaporizer and the separating means, ducts connecting the upper end of the tube with the condenser and the downwardly extending tube, and a by-pass in parallel with the latter and connected thereto to permit the short-circuiting of the lighter fluid which is entrained by the heavy fluid globules when the vaporizer pressure increases.
25. Apparatus of the class described comprising a circuit for a relatively light and volatile fluid, a second circuit for a heavy and less volatile fluid, said first-named circuit including a vaporizer and a condenser, said circuits having a part in common including a downwardly extending tube of restricted diameter wherein globules of heavy fluid entrain bodies of the lighter liquid, separating means at the lower end of said tube, a duct connecting said means to the vaporizer, a lifter tube of restricted diameter also forming a common part of said circuits, wherein vapor from the vaporizer lifts globules of the heavier fluid, ducts connecting the lower end of said lifter tube with the vaporizer and the separating means, ducts connecting the upper end of the tube with the condenser and the downwardly extending tube, the duct connecting the separating means with the lifter tube including a trap containing the heavier fluid and having a leg extending above the separating means, whereby upon starting the apparatus the pressure of the vaporizer will cause heavy fluid to rise in the downwardly extending tube and in said leg of the trap to balance initial vaporizer pressure.
26. Apparatus of the class described comprising a fluid circuit including a vaporizer, a supply duct connected to the vaporizer, a pressure equalizing chamber connected to the duct, a downwardly extending tube of restricted diameter having an end opening into said chamber below its connection with said duct, the lower part of said chamber containing a heavy liquid to seal the end of the tube.
27. Apparatus of the class described comprising a vaporizer, heating means associated therewith, means for supplying a relatively light liquid to the vaporizer and automatically balancing the vaporizer pressure, said means comprising a downwardly extending tube of restricted diameter receiving globules of a heavy liquid to entrain bodies of the volatile liquid therebetween, a chamber, the tube having an open lower end immersed in a body of the heavy liquid in said chamber, a fluid supply duct connecting the chamber to the vaporizer and having an open end in the chamber above the open end of the tube, and a drain for the heavy liquid having a mouth in said chamber above the tube end, but below the duct end.
28. Apparatus of the class described comprising a vaporizer, heating means associated therewith, means for supplying a relatively light liquid to the vaporizer and automatically balancing the vaporizer pressure, said means comprising a downwardly extending tube of restricted diameter receiving globules of a heavy liquid to entrain bodies of the volatile liquid therebetween, a chamber, the tube having an open lower end immersed

in a body of the heavy liquid in said chamber, a fluid supply duct connecting the chamber to the vaporizer and having an open end in the chamber above the open end of the

5 tube, and a drain for the heavy liquid having a mouth in said chamber above the tube end, but below the duct end, said drain forming one leg of a trap, the other leg of said trap being provided with a spill-over outlet above 10 the chamber but below the lower end of the tube.

29. Apparatus of the class described comprising a vaporizer, heating means associated therewith, means for supplying a relatively

15 light liquid to the vaporizer and automatically balancing the vaporizer pressure, said means comprising a downwardly extending tube of restricted diameter receiving globules of a heavy liquid to entrain bodies of the

20 volatile liquid therebetween, a chamber, the tube having an open lower end immersed in a body of the heavy liquid in said chamber, a fluid supply duct connecting the chamber

25 to the vaporizer and having an open end in the chamber above the open end of the tube, and a drain for the heavy liquid having a mouth in said chamber above the tube end, but below the duct end, said drain forming

30 one leg of a trap, the other leg of said trap being provided with a spill-over outlet about the chamber but below the lower end of the tube, a liquid receptacle at the upper end of said tube having cross-sectional dimensions somewhat greater than the tube so that 35 bodies of the heavier liquid will not form separate globules therein.

30. Apparatus of the class described comprising a vaporizer, heating means associated therewith, means for supplying a relatively

40 light liquid to the vaporizer and automatically balancing the vaporizer pressure, said means comprising a downwardly extending tube of restricted diameter receiving globules of a heavy liquid to entrain bodies of the

45 volatile liquid therebetween, a chamber, the tube having an open lower end immersed in a body of the heavy liquid in said chamber, a fluid supply duct connecting the chamber

50 to the vaporizer and having an open end in the chamber above the open end of the tube, and a drain for the heavy liquid having a mouth in said chamber above the tube end, but below the duct end, said drain forming

55 one leg of a trap, the other leg of said trap being provided with a spill-over outlet above the chamber but below the lower end of the tube and a by-pass connected to the drain below the chamber and communicating with

60 the upper part of the tube, whereby high vaporizer pressure forces the lighter liquid through the chamber and the upper part of the drain into the by-pass.

31. Apparatus of the class described comprising a vaporizer, heating means associated therewith, means for supplying a relatively

light liquid to the vaporizer and automatically balancing the vaporizer pressure, said means comprising a downwardly extending tube of restricted diameter receiving globules of a heavy liquid to entrain bodies of the

70 volatile liquid therebetween, a chamber, the tube having an open lower end immersed in a body of the heavy liquid in said chamber, a fluid supply duct connecting the chamber

75 to the vaporizer and having an open end in the chamber above the open end of the tube, and a drain for the heavy liquid having a mouth in said chamber above the tube end, but below the duct end, said drain forming

80 one leg of a trap, the other leg of said trap being provided with a spill-over outlet about the chamber but below the lower end of the tube, a liquid receptacle at the upper end of

85 said tube having cross-sectional dimensions somewhat greater than the tube so that bodies of the heavier liquid will not form separate

90 globules therein and a by-pass connected to the drain below the chamber and communicating with the upper part of the tube, whereby high vaporized pressure forces the

95 lighter liquid through the chamber and the upper part of the drain into the by-pass.

32. Apparatus of the class described comprising a vaporizer, heating means associated therewith, means for supplying a relatively

100 light liquid to the vaporizer and automatically balancing the vaporizer pressure, said means comprising a downwardly extending tube of restricted diameter receiving globules of a heavy liquid to entrain bodies of the

105 volatile liquid therebetween, a chamber, the tube having an open lower end immersed in a body of the heavy liquid in said chamber, a fluid supply duct connecting the chamber

110 to the vaporizer and having an open end in the chamber above the open end of the tube, and a drain for the heavy liquid having a mouth in said chamber above the tube end, but below the duct end, an elongate outlet

115 passage of restricted cross-section connected to the vaporizer and affording resistance to rapid vapor flow, whereby the vaporizer pressure may readily rise in response to an increase in rate of vaporization.

33. Apparatus of the class described comprising a vaporizer, heating means associated

120 light liquid to the vaporizer and automatically balancing the vaporizer pressure, said means comprising a downwardly extending tube of restricted diameter receiving globules of a heavy liquid to entrain bodies of the

125 volatile liquid therebetween, a chamber, the tube having an open lower end immersed in a body of the heavy liquid in said chamber, a fluid supply duct connecting the chamber

130 to the vaporizer and having an open end in the chamber above the open end of the tube, and a drain for the heavy liquid having a mouth in said chamber about the tube end,

but below the duct end, said drain forming one leg of a trap, the other leg of said trap being provided with a spill-over outlet above the chamber but below the lower end of the tube, and a by-pass connected to the drain below the chamber and communicating with the upper part of the tube, whereby high vaporizer pressure forces the lighter liquid through the chamber and the upper part of the drain into the by-pass, an elongate outlet passage of restricted cross-section connected to the vaporizer and affording resistance to rapid vapor flow, whereby the vaporizer pressure may readily rise in response to an increase in rate of vaporization.

34. Apparatus of the class described including an upwardly extending tube of restricted diameter wherein globules of liquid are lifted by vapor pressure, a vaporizer, means for supplying liquid to the lower end of the tube, and means receiving liquid and vapor from the upper end of the tube, an elongate tube of restricted diameter connecting the vaporizer and the lower part of the lifter tube, and providing high resistance to rapid vapor flow, whereby upon initial vaporization substantially the full pressure of the vaporizer may be effective in starting the upward movement of the heavy liquid in the tube and whereby as the rate of vaporization increases the pressure of the vapor is reduced when it reaches the tube.

35. Method of supplying a relatively light liquid to a vaporizer and automatically balancing the vaporizer pressure which involves the employment of a downwardly extending capillary tube wherein globules of a heavier liquid entrain bodies of the light liquid, said method comprising the provision of a pressure balancing column of the heavy fluid to balance the pressure at the lower end of the tube and automatically varying the effective height of the column in response to varying vaporizer pressure thus automatically varying the proportion of the heavier and light liquids in the tube and reducing the amount of liquid supplied to the vaporizer in response to increased vaporizer pressure.

36. Method of supplying a relatively light liquid to a vaporizer and automatically balancing the vaporizer pressure which involves the employment of a downwardly extending capillary tube wherein globules of a heavier liquid entrain bodies of the light liquid, said method comprising the provision of a pressure balancing column of the heavy fluid to balance the pressure at the lower end of the tube and automatically varying the effective height of the column in response to varying vaporizer pressure thus automatically varying the proportion of the heavier and light liquids in the tube and reducing the amount of liquid supplied to the vaporizer in response to increased vaporizer pressure, and causing the tube to be entirely filled with the

heavy fluid thus interrupting further supply of the light fluid to the vaporizer in response to high pressure therein.

Signed by me at Cambridge, Massachusetts this 12th day of December 1930.

LYMAN F. WHITNEY.
